UNITED STATES PATENT OFFICE.

HERMAN SOELLNER, OF BROOKLYN, NEW YORK.

ATTACHMENT FOR DOORS.

1,370,062.

Specification of Letters Patent.

Patented Mar. 1, 1921.

Application filed May 29, 1920. Serial No. 385,169.

To all whom it may concern:

Be it known that I, HERMAN SOELLNER, a citizen of the United States, and resident of the borough of Brooklyn, county of Kings, city and State of New York, have invented 5 certain new and useful Improvements in Attachments for Doors, of which the following is a specification.

My invention relates to doors and more 10 particularly to doors which are hung on hinges comprising two sections pivotally connected by means of removable pintles. Although the latter are located upon the inside, when the door is closed, it has heretofore been possible to remove said pintles from the outside by inserting a suitable instrument between the door and the casing, thus permitting a separation of the hinge sections and a consequent opening of the 15 door whereby an illegitimate entrance may be effected. To prevent such opening of the door, even after the hinge pintles have been removed, bolts have been provided to bridge the joint between the door and casing and to 20 interlock one with the other, said bolts being carried either by the door or the casing and projecting into a suitable recess in the casing or the door when the latter is closed. Because these bolts are capable of being sawed 25 in two through the joint between the door and casing, they have been only partly satisfactory to prevent illegitimate forcing of 30 said door. The particular object of my invention is to overcome these objections by 35 providing bolts of improved construction whereby the door and casing are interlocked and which it is impossible to saw through or otherwise render ineffective when the door is closed. My invention will be fully 40 described hereinafter and the features of novelty will be pointed out in the appended claims.

In the accompanying drawings which 45 illustrate an embodiment of my invention without defining its limits, Figure 1 is an elevation of the casing and door with the latter in its open position; Fig. 2 is a fragmentary face view, partly broken away and on an enlarged scale; Fig. 3 is a section on the line 3—3 of Fig. 2; Fig. 4 is an end view 50 of one form of bolt; and Fig. 5 is a side view partly in section of another form of bolt.

In the drawings, 10 is the door and 11 the door frame or casing, both of which may be 55 of any conventional form and construction, the door 10 being hung in the casing 11 by means of hinges comprising sections 12 secured respectively to the door and its casing and pivotally connected through the medium 60 of removable pintles 13 in the well known way. The customary strip 14 is attached to the casing 11 by means of nails or other fastening devices 15 adjacent to the hinged edge of said door. As so far described, the 65 construction and arrangement may be of any well known type and may include any features commonly found in doors of the kind in question.

My invention comprises a metallic mem- 70 ber 16, which for convenience of description I have termed a bolt and which is provided with a recess 17 in which a freely moving insert 18 is located, said insert being preferably in the form of a hardened steel ball of 75 a diameter to substantially fill the recess 17 and yet be freely movable therein. The form or shape and dimensions of the insert 18 are optional, the essential requirements being that it must be freely movable in the 80 recess and should be constructed of a material which is not readily cut or otherwise severed.

In use the bolt 16 may be mounted upon the door 10 in registry with a pocket 19 85 formed in the door casing 11, the parts being so arranged and proportioned that, when the door is closed, the bolt will bridge the joint a between said door and casing and project into the pocket 19, the ball or other 90 insert 18 being in registry with said joint a as shown in Fig. 2. Or if desired, the bolt 16 may be fixed in the casing 11 in which case the coöperating pocket 19 is formed in the door 10, the operation and location of 95 the parts being otherwise just the same as previously described.

In some instances it may be desirable to provide a plurality of bolts carried either by the door or by the casing or, as shown 100 in Figs. 1 and 2, alternately fixed upon said door and casing. The bolt 16 may be positioned so that its axis extends at right angles to the upright edge of the door or casing in which event the ball or other 105 insert 18 may be prevented from falling out

of the recess 17 by magnetizing the bolt 16 or by upsetting the metal at its free end as indicated at *b* in Fig. 5; or the bolt 16 may be located with its axis inclined downwardly 5 relatively to the edges of the door or casing, as shown at the lower portion of Fig. 2. The bolt 16 may be externally screw-threaded and screwed into the door 10 or casing 11 in which case the recess 17 is of hexagonal or other angular cross-section as shown 10 in Fig. 4 for the accommodation of a suitable tool whereby rotation of the bolt on its axis is facilitated or said bolt may be smooth as in Fig. 5 and simply be driven into the 15 door or casing and held therein by friction.

It will be noted, when the door is closed and locked that the bolt or bolts 16 bridge the joint *a* between the door and its casing and interlock the same, so that even if the 20 pintles 13 have been successfully removed from the hinges by means of a suitable tool inserted between the door and casing after the strip 14 has been removed, it will be impossible to move the door out of the casing. 25 If upon realizing this an intruder should attempt to sever or cut the bolts 16 by inserting and operating a thin saw or other cutting tool between said door and casing, such attempt will be frustrated the moment 30 the saw or other cutting tool reaches the freely movable insert 18. A continuation of the attempt to cut the bolts after this has happened will either simply cause the insert to rotate under the action of a saw or 35 otherwise jam or wedge the saw between the insert and the bolt against further actuation; the insert will also positively prevent a chisel from being successfully used to cut the bolt, by deflecting and chipping said 40 chisel and thus rendering it useless to force an illegitimate entrance.

My invention is extremely simple in construction and efficient in operation and is easily and quickly placed in operative position 45 without the necessity for skilled labor. The presence of the invention in no way interferes with the normal, intentional operation of the door as such.

Various changes in the specific form 50 shown and described may be made within

the scope of the claims without departing from the spirit of my invention.

I claim;

1. The combination of a door frame, a door hung therein, one of said elements being provided with a pocket, and the other element having a recess arranged to register with said pocket, and a spherical insert loosely mounted in said recess, and projecting beyond the joint between the door and the frame into said pocket. 55

2. The combination of a door frame, a door hung therein, one of said elements being provided with a pocket, a recessed bolt fixed upon the other element and projecting 65 therefrom across the joint between said door and frame into said pocket, when the door is closed, and a spherical insert loosely mounted in the recess of said bolt in registry with said joint. 70

3. The combination of a door frame, a door hung therein, one of said elements being provided with a pocket, a recessed bolt fixed upon the other element and projecting therefrom across the joint between said 75 door and frame into said pocket when the door is closed, the axis of said bolt being inclined in a vertical plane, and a spherical insert loosely mounted in the recess of said bolt in registry with said joint. 80

4. The combination of a door and its casing and an attachment arranged to bridge a joint between said door and casing for preventing forcing of the door, said attachment comprising a bolt having an axial recess 85 open at one end and a spherical insert loosely mounted in said recess. 90

5. The combination of a door and its casing and an attachment arranged to bridge a joint between the said door and casing for preventing forcing of the door, said attachment comprising a bolt having an axial recess open at one end, a spherical insert loosely mounted in said recess, and means for maintaining said insert against unintentional removal from said recess. 95

In testimony whereof I have hereunto set my hand.

HERMAN SOELLNER.
